United States Patent Office.

WILLIAM HEYLMAN, OF PEORIA, ILLINOIS.

Letters Patent No. 89,764, dated May 4, 1869.

IMPROVEMENT IN DEVICE FOR BENDING PLOW-HANDLES.

The Schedule referred to in these Letters Patent and making part of the same.

To all whom it may concern:

Be it known that I, WILLIAM HEYLMAN, of the city and county of Peoria, and State of Illinois, have invented a new and improved Machine for Giving the Required Curves in PLOW-HANDLES; and I do hereby declare that the following is a full, clear, and exact description of the construction and operation of the same, reference being had to the accompanying drawings, making a part of this specification, in which—

Figure 1 is a perspective view.

Figure 2 is an end elevation.

Figure 3 is a rear view.

Figures 4 and 5, views of lever-box.

Figure 6 is an end view of upper "former."

Figure 7 is a side view of same.

Figure 8 is a side view of lower "former."

Figure 9 is an end view of the same.

Like letters, in the figures of the drawings, indicate like parts.

This machine, or apparatus, is for bending and at the same time twisting permanently pLOW-HANDLES and other wooden objects. It is particularly fitted for giving handles such a curve as will fit the mould-board of a pLOW without using any tool for that purpose.

The machine is constructed of heavy timbers, resting on a proper base, A A A.

The drawings represent but six sections of the machine, each space formed by the uprights B F B, and transverse bars *a b c* constitute a section, each section to hold and mould ten pLOW-handles.

The drawings represent but one or two formers in proper place. Ten can be ranged side by side in each section. In these sections the upright timbers are seven in number, four on each end, B C D E, and three in the centre, F G H. The upright D is three times the size of the others.

The upright timbers carry the horizontal timbers *a b c*, the latter being attached to the uprights C F C. The horizontal timbers *a b c* are so constructed as to present an inclined surface outwardly.

The central three horizontal timbers, *d e f*, in the immediate rear of the latter-described timbers, are adjustable by means of slots at the ends and centre of each timber, secured by bolts or wood-screws, to allow of the adjustment of distances between the timbers for the admittance of thin and thick handles, and correspond with the required width between the upper and lower "formers" *m n*.

The three stationary horizontal beams *g h h h*, in the rear of those just described, and the same bolted to the uprights D G D, are from one to three inches below the level of those marked *d e f*, and sustain the rear "former" *m*, which latter is bolted to its under side.

In the rear, and alongside of these last beams *g h h*, are placed the adjustable horizontal beams *i j v v*, which are suspended to the iron cross-bars *v v* by the adjustable hooks *w w*, or their equivalents.

The "formers," or moulding-blocks *m n*, are made of cast-metal, from any form or shape of mould-boards of pLOWS, of any fashion or shape desired, and to shape handles to fit the mould-board of pLOW without cutting, &c. They have curved surfaces to receive the pLOW-handle, and by which the curve in the wood is accomplished, and a rim or flange at either side to retain the handle during the bending-process.

The "formers" are made by taking a cast from the mould-board, and constructing the mould for the "formers" from that pattern. Then the former is cast, thus securing a perfect model of the curve in the mould-board. Besides the general curve or recurve in a pLOW-handle, the formers may be so modelled as to give an oblique curve at any desired angle.

To the "former" *m* are attached the iron strap *o* and bar *p*, connected with the "holder" *q*. The use of the strap is to keep the fibres of the handle, in bending it, from springing up and breaking the surface.

After the handle is inserted between the "formers," the holder *q* is further secured to the wood by passing over it the hinged iron bar *r*, which is secured under the hook *s* of the holdfast *t*. The bar *p* contains four or five holes, one inch apart, by which the holder *q* is adjusted to long or short wood. The holdfast is bolted (so as to receive any inclination) to the bars *a b*, and *c*.

The lower part of the pLOW-handle, or that part adjusted to the lower part of the mould-board, and fastened to the inside of the bar of the pLOW which runs next to the landside when the pLOW is at work, is fastened in position by means of the balanced hook *u*, one hook to catch former and handle.

The operation of this machine is as follows:

The wood for handle, after being properly steamed, is inserted between the "formers" *m n*, the lower end of handle projecting beyond the upper former. The strap *o* and holder *q* are brought down over it, and the bar *r* of holdfast *t* secured over it, having first adjusted the horizontal beams *d* and *g*.

On the end of the handle, projecting beyond the upper "former," is placed the iron box *M*, on the top of which is a curved clamp, *L*, sharpened on the lower edge, and adjustable by means of a thread-bolt and nut, designed to bite into the wood when the lever is raised, and the box serving to retain the fibres in their places, and keep the end of handle from splitting or splintering.

The box has an arm, *L*, projecting from one end, by which the twist or turn is given to the wood.

The upper end of arm *L* receives, by means of a hole, the hook of the lever *Z*, at the same time that the hook on upper side of lever is placed over the bar *X*.

On depressing the handle of lever, the box draws up the end of the handle obliquely, or higher on the side on which the arm *K* projects.

The straps *o* and bar *p*, together with the holder *q*, attached to the former *m*, and resting on the horizontal

beams *e* and *h*, are raised up out of the way by means of the lever *b b*, resting on the cross-bar running between the uprights *B* and *l*.

The front bars *a*, *b*, and *c*, work independently of one another, to suit the convenience of the operator. The same remarks apply also to the horizontal beams *d*, *e*, and *f*, excepting *d*, which is blocked beneath, and that of *e*, which has slotted holes, operating to regulate the distance between the "formers" for thick or thin plow-handles.

It is designed that the frame shall be constructed to contain from sixty to five hundred or one thousand "formers," with appliances, so that an unlimited number of plow-handles may be shaped at one time.

Having thus fully described my invention, What I claim therein as new, and desire to secure by Letters Patent, is—

1. The formers *m n*, when constructed as herein described and for the purpose set forth.
2. The adjustable horizontal bars *a b c*, and *d e*,

and *f*, operated in the manner and for the purpose as described.

3. The combination of the formers *m n* with the bars *d* and *g* of the frame-work, substantially as described.

4. The adjustable bar or slide *X*, lever *Z*, uprights *y y*, box *M*, arm *K*, adjusting-clamp *L*, balanced hook *u*, and adjustable beam *i*, combined and operated as described.

5. The formers *m* and *n*, strap *o*, bar *p*, holder *q*, hinged bar *r*, holdfast *t*, and catch *s*, combined and operated as described.

6. The combination of the levers *b b* with the iron uprights *l l* and cross-bars or supports, and uprights *B B*, for holding up strap, bar, and holder *q*, substantially as described.

WILLIAM HEYLMAN.
